UNITED STATES PATENT OFFICE.

SAMUEL M. GUSS, OF POTTSTOWN, ASSIGNOR OF ONE-HALF TO JACOB S. AMMON, OF READING, PENNSYLVANIA.

PEEL FOR HEATING-FURNACES.

SPECIFICATION forming part of Letters Patent No. 402,588, dated May 7, 1889.

Application filed March 24, 1888. Serial No. 268,329. (No model.)

To all whom it may concern:

Be it known that I, SAMUEL M. GUSS, a citizen of the United States, residing at Pottstown, in the county of Montgomery and State 5 of Pennsylvania, have invented certain new and useful Improvements in Peel's for Heating-Furnaces; and I do declare the following to be a full, clear, and exact description of the invention, such as will enable others skilled 10 in the art to which it appertains to make and use the same, reference being had to the accompanying drawing, and to the letters and figures of reference marked thereon, which form a part of this specification.

15 This invention relates to an apparatus intended more particularly to be used for charging heating-furnaces with metallic piles, ingots, blooms, &c., and for withdrawing the same.

20 It consists in a construction which permits the peel, whether light or loaded, to be suspended in equilibrium, if desired; also, in details of construction, as fully set forth and claimed herein.

25 The drawing shows a side elevation, partly in section, of my apparatus suspended from above the roof of a furnace to which it is supplying a pile of metal to be heated.

H represents an ordinary heating-furnace 30 with charging-door H³. The pile L is shown in position on the blade J' of the peel, ready to be lowered to the bottom H' of the furnace. This blade, which may be eight inches wide, (more or less,) is rectangular in section, and

35 is secured to the peel-bar J by pushing one end into a socket, J³, and pinning it, as shown, or in any equivalent manner which will permit the blade to be readily moved and replaced. The peel-bar J is provided at its op-

40 posite end with a toothed quadrant, J², and is pivoted at A² to the bent arm A, which rises vertically and then bends to about a right angle over the roof H² of the furnace, while at the bottom it is bifurcated and bent

45 at about right angles in the opposite direction, the peel-bar J, to which the blade is secured, being adapted to swing vertically in the bifurcated extension-arm A'. A worm, K, on a vertical shaft, K', with hand-wheel

50 K², is supported in the closed end of this extension-arm and adapted to gear with the

toothed quadrant J², and the guide-handle B, with the usual cross-piece near its far end, is also securely fastened to the extension-arm A'. A counterbalance-weight, D, is adjustably 55 supported on the horizontal slide-bar C, projecting from the upper bend of the arm A. The latter is suspended at one of the points A³, about vertically above the center of pile L, to a swivel, E, adapted to run on an over-head track or crane-jib, G.

The operation of my apparatus is as follows: The peel when light may be balanced by adjusting the weight D so that the blade J' will naturally hang in about a horizontal 65 position, and as the center of load L is adapted to come about vertically under the point of suspension this equilibrium may be approximately maintained with any weight of pile. In order to raise or lower the blade J' without changing the horizontal position of the guide-handle, the hand-wheel K² may be turned in the proper direction, and the worm K, acting upon the toothed quadrant J², will effect the desired object.

70 The steel blade J', which is exposed very frequently to the intense heat of the furnace, may be readily reversed or replaced without affecting the remainder of the apparatus. The weight, being suspended in equilibrium, 80 may be handled and guided with a much smaller force of men and with greater speed and safety than with a form of peel such as is commonly used, which requires a large force of men merely to balance the weight of the pile 85 in transferring it to and from the furnace.

I do not wish to confine myself to the construction shown in the drawing, the gist of my invention consisting in movably suspending the peel, so that whether light or loaded 90 it will be approximately in equilibrium, and in making the blade adjustable vertically independently of the guide-handle.

I am aware that Patent No. 134,151 shows a bent bar, by means of which the pivotal point 95 of the peel is introduced into the furnace in charging. This, however, is not adapted to support the load in equilibrium, and I do not desire to claim such a construction.

What I desire to secure by Letters Patent 100 are the following claims:

1. An apparatus for charging furnaces, con-

- sisting of a peel secured to a bent arm mova- | 4. The combination of the bent arm, the
bly suspended at a point vertically above a | operating-handle, the pivot-blade, with a quad-
weight on the peel-blade J', substantially as | rant, J², and the worm K, all arranged sub-
